UNITED STATES PATENT OFFICE.

FREDERICK C. OVERBURY, OF HILLSDALE, NEW JERSEY, ASSIGNOR, BY MESNE ASSIGNMENTS, TO THE FLINTKOTE COMPANY, OF BOSTON, MASSACHUSETTS, A CORPORATION OF MASSACHUSETTS.

ORNAMENTAL ROOF.

1,265,105.

Specification of Letters Patent.

Patented May 7, 1918.

Application filed August 12, 1915. Serial No. 45,206.

To all whom it may concern:

Be it known that I, FREDERICK C. OVERBURY, a citizen of the United States, and a resident of Hillsdale, in the county of Bergen and State of New Jersey, have invented 5 certain new and useful Improvements in Ornamental Roofs, of which the following is a specification.

This invention has relation to roofs for 10 dwellings, public buildings, barns and other edifices, where an ornamental effect is desirable, and has for its object to provide certain improvements in roof coverings by which striking and unusual designs may be 15 secured with relatively thin flat roofing materials, so as to give thereto, the appearance of solidity and the visual effect produced by raised tiles.

In accomplishing this result, I employ 20 roofing elements made of waterproofed felt or analogous material surfaced with colored weatherproof material. For example, I may use individual shingles formed of such material, but generally I prefer to employ 25 roofing strips having on their elongated edges tabs or projections of suitable configuration, which, when the strips are laid in overlapping relation, simulate tiles or shingles.

30 On the accompanying drawings,—

Figure 1 represents a roof covering embodying the invention.

Figs. 2 and 3 represent the individual elements employed in forming the last-mentioned roof covering.

Fig. 4 represents other forms or pairs of overlapping roofing strips which I may employ.

In the formation of the individual roofing 40 elements, I use a sheet of felt or equivalent fibrous material saturated with asphalt or other equivalent waterproofing compound, coat the same with a layer of harder asphalt or pitch, either having incorporated therein 45 a suitable pigment or else having embedded therein a layer of crushed mineral material.

In some cases the mineral material may be 50 formed with alternating bands or stripes of different colors according to the effect to be produced. The sheet thus formed is cut into individual shingles by suitable machinery, or is severed transversely into shingle strips having on one or both longitudinal edges

spaced tabs or projections of predetermined configuration.

55

I will explain the invention in connection with the use of shingle strips. Preferably, though not necessarily as will be subsequently explained, these strips may be provided in two different colors or shades and 60 they are arranged in pairs on the roof so that the rows of strips of one color alternate with the rows of the strips of the other color.

I have illustrated forms of strips, by 65 which, when they are laid, a roof covering is formed which gives the appearance of a roof formed of thick bricks arranged in step form. Fig. 2 illustrates a shingle strip 24 having the rectangular tabs or projections 70 25 separated by the parallel side recesses 26 perpendicular to the line lying at the ends of the tabs. Fig. 3 shows the other strip of the pair as indicated at 27, and it is provided with tabs or projections 28 which are 75 substantially trapezoidal, spaced by the parallel-sided recesses 29 which are at an acute angle to a line lying at the ends of the tabs or projections. These strips, which may be of the same color or of different colors, are 80 laid in pairs, as shown in Fig. 1, with the recesses of one strip substantially registering with the recesses of the other strip of the pair.

In Fig. 4, I have shown that, in lieu of 85 the strip 27 having the straight inclined recesses spacing, or intervening between, the tabs, I may provide strips 30 formed with recesses 31 which are curved upwardly and laterally, so that the tabs when laid look like 90 horizontally arranged curved tiles.

It is difficult in drawings, such as form a part of this specification, to illustrate the illusory effect produced by roofing elements such as herein described. Nevertheless, 95 when the roofing elements are made full-size and are laid in accordance with the directions given herein, the user will secure the effects which I have described.

Having thus explained the nature of my 100 said invention and described a way of making and using the same, although without attempting to set forth all of the forms in which it may be made or all of the modes of its use, what I claim is:

105

A roof covering consisting of a plurality

of flat flexible shingle strips laid in overlapping horizontal rows and having spaced tabs or projections on their exposed lower portions, the strips in one row having exposed portions formed with substantially rectangular tabs with substantially parallel intervening vertical recesses, and the strips

of an adjacent row having on their exposed portions tabs and intervening recesses extending upwardly and laterally. ¹⁰

In testimony whereof I have affixed my signature.

FREDERICK C. OVERBURY.
